The ornamental design for a towel heating bucket as shown and described.

DESCRIPTION

FIG. 1 is a perspective view of a towel heating bucket showing my new design;
 FIG. 2 is another perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof;
 FIG. 8 is a bottom plan view thereof; and,
 FIG. 9 is an enlarged view of portion 9 shown in FIG. 1.
 The broken lines in the drawings depict portions of the towel heating bucket that form no part of the claimed design.
 The dot-dash broken lines represent boundaries of the enlarged portions and form no part of the claimed design.
